(57) **CLAIM**

We claim the ornamental design for a wear member, as shown and described.

DESCRIPTION

FIG. 1 is a bottom view of a wear member, showing our new design;

FIG. 2 is a left side view thereof;

FIG. 3 is a right side view thereof;

FIG. 4 is a top sectional view thereof, taken along line A-A in FIG. 5;

FIG. 5 is another left side view thereof, the broken line labeled as A-A and B-B indicates a sectional view plane and forms no part of the claimed design;

FIG. 6 is a bottom sectional view thereof, taken along line B-B in FIG. 5;

FIG. 7 is a left rear lower perspective view thereof;

FIG. 8 is a right rear lower perspective view thereof;

FIG. 9 is a left rear upper perspective view thereof;

FIG. 10 is a right rear upper perspective view thereof;

FIG. 11 is a right rear view thereof;

FIG. 12 is a rear view thereof;

FIG. 13 is a left rear view thereof; and,

FIG. 14 is a front view thereof.

The broken lines in the drawings depict portions of the wear member that form no part of the claimed design.
